TABLE OR THE LIKE

Richard G. Reineman, Covina, Calif., and George E. Schaefer, Muskegon Heights, Mich., assignors to Brunswick Corporation, a corporation of Delaware

Filed Apr. 11, 1960, Ser. No. 60,122

Term of patent 14 years

(Cl. D33—14)

FIG. 1 is a top plan view of a table or the like showing our new design;

FIG. 2 is a side elevational view thereof; and
FIG. 3 is an end elevational view thereof.

The dominant features of our design are shown in full lines on the drawing, and comprises a wall mounted table having tapering sides and an outer end in association with an inclined tapered leg and a brace member, all as shown.

In FIG. 2, the broken line showing of the wall surface is for illustrative purposes only.

We claim:

The ornamental design for a table or the like, as shown and described.
